UNITED STATES PATENT OFFICE.

DANIEL W. COLE, OF BALDWIN, KANSAS, ASSIGNOR OF ONE-HALF TO JOHN J. WRIGHT AND JOHN P. WOODS, OF SAME PLACE.

HEATING-STOVE.

SPECIFICATION forming part of Letters Patent No. 596,693, dated January 4, 1898.

Application filed December 16, 1896. Serial No. 615,879. (No model.)

To all whom it may concern:

Be it known that I, DANIEL W. COLE, a citizen of the United States, residing at Baldwin, in the county of Douglas and State of Kansas, 5 have invented certain new and useful Improvements in Heating-Stoves; and I do hereby declare the following to be a full, clear, and exact description of the invention, such as will enable others skilled in the art to which it appertains to make and use the same.

My invention relates to improvements in oil heating-stoves embracing a novel construction of hydrocarbon-burner and a novel form of heating-drum or stove-body, as will 15 be hereinafter fully described and claimed.

I have illustrated my improved heating-stove in the accompanying drawings, forming a part of this specification, in which—

Figure 1 is a perspective view of my improved stove. Fig. 2 is a vertical central sectional view through the same. Fig. 3 is an enlarged sectional elevation through the hydrocarbon-burner of the stove. Fig. 4 is a detail sectional view through the upper part 25 of the stove drum or body, showing the arrangement of the heating-flues thereof.

Like letters of reference denote corresponding parts in all the figures of the drawings.

I will proceed to describe the improved hydrocarbon-burner shown more clearly by Fig. 3 of the drawings.

A designates the generator, and B is the retort, both of which are cast with the web C in a single piece of metal.

35 The generator A is in the form of a cylinder, and the retort B is likewise in the form of a cylinder, having integral heads b closing its ends. The retort B is arranged above the generator A in substantially the same vertical plane with the same, and the retort and generator are united by the integral web C, which extends longitudinally between the retort and generator. The generator A is divided into vapor and steam compartments A' A'' by a central transverse partition a', and in like manner the retort B is subdivided by the partition b' into the vapor and steam chambers B' B''.

On its lower side the generator A is provided with the integral bosses or enlargements d d', (indicated by dotted lines,) which

extend a short distance below the cylindrical surface of the generator, and in these bosses are formed or tapped holes in which may be screwed the threaded upper ends of the supply-pipes E E', (shown by dotted lines,) which pipes convey the hydrocarbon oil and water to the respective chambers A' A'' of the generator A, said pipes E E' leading from a suitable tank to supply water and oil to the pipes. 55 The enlargement of the generator by the bosses d d' imparts greater strength to the generator at the places where the supply-pipes are connected to the retort, and the joint thus secured effectually prevents the leakage of 60 the vaporized fuel and steam from the generator.

I prefer to connect the water and oil pipes E E' by leading them through the ends or heads of the chambers A' A'' of the generator, 70 and these pipes are extended into the chambers A' A'' nearly or wholly throughout the length thereof. The inner ends e e' of these supply-pipes are perforated, as shown by Fig. 3, or provided with a screen which serves to 75 retain any sediment that may be contained in the oil or water, and which causes the oil to be supplied slowly, by drops, to insure the thorough vaporization of the liquid, said pipes also affording an increased heating-surface 80 within the generator.

The vapor and steam from the chambers of the generator A pass into the retort-chambers by means of vertical slots or passages F F', which are formed in the connecting-web C at 85 the time the retort and generator are cast.

On the upper side of the retort B are cast the integral bosses g g', similar to the bosses d d', that may be cast on the generator, and in these bosses g g' are tapped holes, into 90 which are screwed the threaded upper ends of the vapor and steam pipes H I, which are in communication with the chambers B' B'' of the retort B. These pipes H I are curved or provided with elbows h h, and they pass along- 95 side of the retort and generator and extend for some distance below the retort. The lower ends of these vapor and steam pipes H I are provided with the elbows i i', which are curved inwardly toward each other and 100 upwardly toward the retort, and the free ends of these elbows i i' are provided with the jets

or tips J J'. The jet or tip J' of the steam-pipe E terminates below and at one side of the tip J on the vapor-pipe E', and these tips are arranged to discharge into the mixing 5 chamber or hood K, which is fastened to the elbow i i' by wires or other suitable fastening contrivance, the hood K being provided with a transverse flame-slot at its upper end, whereby the steam and vapor discharged 10 from the pipes into the hood are commingled therein to produce a gas, which issues from the slot in the hood and is consumed below the retort and generator to heat the same.

The pipes H I are provided with the con- 15 trolling-valves L, of any suitable construction, for regulating the flow of vapor and steam from the retort to the tips that discharge to the mixing hood or chamber.

During the process of casting the retort 20 and generator I form therein vent holes or apertures m m, which prevent "blowing" of the casting, and these vent-apertures are provided with screw-threads to receive the threaded plugs M M, which are each made of 25 a solid piece and threaded to screw into the vent-apertures m, whereby the retort or generator can be cleansed by detaching the plugs M.

To secure uniformity in the distribution of 30 the heat, the burner is inclosed within a suitable casing N, (shown in Fig. 2,) which is constructed to permit of ready access to the valves and to enable it to be removed when it is desired to inspect or clean the burner, 35 the casing N being provided with a transverse slot n at its upper end through which the flame issues and by which it is spread into a fan-like sheet.

In operation the oil and water are supplied 40 by the pipes E E' to the chambers of the generator A, in the separate chambers A' A² of which the oil is vaporized and the water converted into steam, and the steam and vapor are then passed through the slots or passages 45 F F' to the retort-chambers B' B'', in which the vapors are superheated by the highly-heated retort. The vapor and steam thus produced pass into the vapor and steam pipes H I, which conduct the same to the jets or tips 50 J J', and owing to the arrangement of the steam-jet J' below and at one side of the vapor-jet J the steam impinges against the vapor as they enter the mixing-chamber K, thus commingling the vapor and steam thoroughly 55 in the hood and producing a gas. The gas issues through the slot in the hood K and is ignited below the retort and generator, and the flame from the hood passes up and around the retort and generator to heat the same and 60 issues through the slot n in the casing N, from which slot n the flame issues in a fan-like sheet.

The hydrocarbon-burner is mounted in a base M', which has the usual feet m', the guard- 65 rail m'', and a flanged seat m''', to which is fitted the stove drum or body N', the latter being easily removed by simply lifting it off

the base. The drum or body N' may be made of sheet metal or other appropriate material, and it is provided with a door n' and with an 70 observation-window n''. The head n''' of this drum is arched or crowned, and it is provided with a socket or seat o, in which is fitted the supply-tank O, a suitable packing O', of asbestos or other heat-resisting medium, being 75 provided around the tank to prevent the vaporization of the liquids contained in the tank by the heat of the stove. Said tank I is divided by a transverse partition into two compartments to contain the liquid hydrocarbon 80 and the water to be supplied to the vaporizer, and with said compartments are connected the pipes E E', leading to the vaporizer.

The stove drum or body N' is constructed with the heat-flues arranged in pairs at Q Q'. 85 (Indicated in Fig. 4.) Any desired number of pairs of these flues may be provided for the drum—as, for example, I may use two pairs arranged on opposite sides of the drum or four pairs arranged equidistant around the drum. 90 The flue Q of each pair is attached on the inside of the drum, and it is closed at its lower end and open at the upper end. The outside flue Q' of the pair is attached to the drum opposite to the inside flue Q, and said outside flue 95 is closed at its upper end and open at the lower end. In the drum N', near the upper closed end of the outside flue Q', is provided a port or opening R' for the passage of the hot air to the flue Q', which conducts the same 100 downward and discharges the hot air toward the floor of the room. Another port R is provided in the drum N' at a point near the closed lower end of the inside flue Q. These flues provide conduits for the air to discharge 105 the same toward the floor of the room.

I also provide the stove with an external illuminating tip or burner S, which is attached to a pipe s, leading to the retort of the hydrocarbon-burner, said pipe s being shown by 110 dotted lines in Fig. 2 and containing a packing of wire-gauze to keep back the pressure of gas to the flame burning at the tip S. A suitable valve is provided in the pipe s to regulate the flow of gas.

In my invention the retort A A' vaporizes the oil and water very quickly, and the vapor and steam pass into the superheating-chambers B B', by which they are superheated before they commingle together. The pipes E E' conduct the superheated vapor and steam downward and discharge the same in streams through the jets J J', and as the superheater and the pipes become very hot the vapor and steam emerge in a dry and heated condition. 115 The stove-body being heated and confining, in a measure, a body of highly-heated air, the heat practically consumes all the odor, soot, and smoke passing through the stove. The air passes through the base up to the generator or hydrocarbon-burner, and the air is heated by said generator, by the drum, and by 120 commingling with the heated air in the drum or body, and the drum or body radiates the heat 125 130

and also discharges the heated air through the flues Q Q' toward the floor of the room.

Having thus fully described my invention, what I claim as new, and desire to secure by 5 Letters Patent, is—

1. The generator A and retort B situated one above the other and joined together by the integral web C, all cast in a single piece; said retort B divided by the partition b' into 10 non-communicative chambers B, B', and the generator A likewise divided by partition a into non-communicative chambers A, A'; said chambers A', B' and the chambers A², B² being connected by the passages F, F' respectively produced in the web C, in combination with the feed-pipes E, E' provided with perforated elbows e e which are arranged within the chambers A', A² of the generator, and the pipes H, I, coupled to the chambers B', B'', 15 20 of the retort, substantially as described.

2. A hydrocarbon-burner comprising an enclosing casing, the generator situated therein and having the non-communicative steam and

vapor chambers, supply-pipes to the generator, the vertical vapor and steam pipes H, 25 I, connected to said generator and having the inwardly-turned elbows below the generator, the jet-nipples J, J' on the inner ends of said vapor and steam pipes and with the discharge-orifice of the nipple J' situated below and inclined toward the other nipple J to direct the current issuing from said nipple J' to impinge against the current from the other nipple J, and a mixing-casing K supported over and around the discharge-nipples J, J' and provided with a transverse slot, n, in its crown, 30 35 substantially as and for the purposes described.

In testimony whereof I affix my signature in presence of two witnesses.
